UNITED STATES PATENT OFFICE.

SIMON G. ROSS AND FRANK B. FREEMAN, OF CINCINNATI, OHIO, ASSIGNEES TO UNITED SHOE MACHINERY COMPANY, OF PATERSON, NEW JERSEY, A CORPORATION OF NEW JERSEY.

SKIVING-MACHINE.

1,080,171.

Specification of Letters Patent.

Patented Dec. 2, 1913.

Application filed May 27, 1909. Serial No. 498,654.

To all whom it may concern:

Be it known that we, SIMON G. ROSS and FRANK B. FREEMAN, citizens of the United States, residing at Cincinnati, in the county of Hamilton and State of Ohio, have invented certain new and useful Improvements in Skiving-Machines; and we do hereby declare the following to be a full, clear, and exact description of the invention, such as will enable others skilled in the art to which it appertains to make and use the same.

The invention relates to a skiving machine adapted for use in reducing the thickness of the projecting edge of the sole of a boot or shoe to give the sole a lighter or thinner appearance.

It has been customary heretofore to reduce the thickness of the projecting edge of the shank portion of the shoe sole in forming light edge shanks by machines adapted to skive the outer edge of the welt of a welted shoe after the welt has been attached to the upper and insole, either before the outsole has been applied to the shoe, or after the outsole has been laid on the shoe, but before the outsole and welt have been secured together. In either case the skiving of the lower edge of the welt results in an increase in the distance of the projecting edge of the completed sole from the upper when the welt and outsole have been united by the outseam, so that the leveling of the sole to secure a close shank is rendered more difficult.

It is the object of the present invention to provide a machine for reducing the thickness of the projecting edge of the shoe sole to form a thin edge shank by removing a skiving from the lower edge of the outsole outside of the channel flap, thus enabling a close shank to be more easily and uniformly produced by the subsequent leveling operation.

It is also the object of the invention to provide a skiving machine which may be utilized in removing a skiving from the outer edge of the outsole around the forepart of a shoe to produce a light edge sole around this part of the shoe.

To these ends one feature of the invention contemplates the provision in a machine provided with a skiving knife arranged to remove a skiving from the lower outer edge of the sole of a shoe, and with a work support and feed roll arranged to engage the

upper and lower side of the projecting edge of the sole, of a guard arranged to lie between the feed wheel and channel flap. The arrangement of the guard between the feed wheel and channel flap enables the shoe to be so guided that the skiving knife may cut close up to the face of the channel flap without danger of injury thereto in operating upon the soles before the outsole and welt have been united by the outseam, and also enables the shoe to be so guided that the skiving knife may cut close up to the outseam without danger of injury thereto, in case the machine is used to skive the edge of the outsole after the outsole and welt have been secured together by the outseam. This guard referred to is preferably arranged to engage the outsole channel, and when so arranged acts as a gage to determine the depth to which the teeth of the feed wheel may penetrate the work, and also to determine the thickness of the skiving which shall be removed by the skiving knife.

The provision of such a gage for engaging the lower side of the sole in a machine for skiving the lower outer edge of the sole of a shoe, constitutes a further feature of the invention, and it is not material to this feature whether the gage also acts as a guard for protecting the channel flap or outseam.

A further feature of the invention contemplates the provision in a machine for skiving the lower outer edge of the sole of a shoe, of a gage for guiding the shoe by engagement with the channel flap. The provision of this gage enables uniform skiving to be readily removed from the lower outer edges of the soles around the foreparts of shoes provided with extension edge soles, and also assists the operator in properly guiding the shoe when operating upon the shanks of shoes. It is referred to employ the guard above referred to as the gage for guiding the shoe by engagement with the channel flap, although this is not essential to this feature of the invention in its broader aspects.

In addition to the features of invention above referred to, the invention also includes certain devices, combinations and arrangement of parts which will be hereinafter described and claimed, the advantages of which will be obvious to those skilled in the art.

The various features of the invention are illustrated in the accompanying drawings, in which—

Figure 1 is a side elevation of a machine embodying the various features of the invention in their preferred forms; Fig. 2 is a plan view of the machine shown in Fig. 1; Fig. 3 is a front elevation; Fig. 4 is a vertical sectional detail through the axis of the feed roll and work support; and Fig. 5 is a detail view of the skiving knife.

In the machine shown in the drawings, the upper side of the projecting edge of the sole (comprising the welt and out-sole) is engaged and supported by a work support 1, while the lower side of the sole is engaged by a coöperating feed roll 2, the work support and feed roll acting to advance the work against a knife blade 3 which is arranged to remove a skiving from the lower edge of the outsole outside the channel flap. The work support is frusto-conical in shape, and is so supported upon a spindle 4 that its conical surface engages the upper surface of the projecting edge of the sole. The work support is also so shaped that it may enter the crease between the upper and the projecting edge of the sole, and act not only as a work support for supporting the sole in position to be acted upon by the skiving knife, but also act as a gage for guiding the shoe by engagement with the last or inseam. The work support is continuously driven through beveled gearing 5 connecting the work support with a shaft 6 which is mounted in fixed bearings in the frame of the machine. The shaft 6 is driven from the main driving shaft 7 through a gear 8 secured to the main driving shaft, and engaging a gear 9 secured to the shaft 6.

The feed roll 2 is secured upon the front end of a shaft 10, and is continuously driven in a direction to coöperate with the work support 1 through gearing 11 connecting the shaft 6 with the shaft 10. The feed roll shaft 10 is mounted in a vertically movable head 12, the rear end of which is pivotally supported at 13 upon the frame of the machine, and the front end of which is guided in a vertical guideway 14 formed in the frame. The feed roll is forced yieldingly toward the work support so that it may accommodate itself to variations in the thickness of the sole by a spring 15 surrounding a rod 16, the upper end of which is pivotally connected to the head 12. The rod 16 passes through a lug 17 on the frame of the machine, and the spring is interposed between this lug and a collar 18 secured to the rod. The movement of the feed roll toward the work support is limited by a stop screw 19 which is threaded through a split lug 20 on the head 12, and is arranged to engage a fixed lug 21 on the frame of the machine. By adjusting the stop screw, the relative

position of the work support and feed roll may be adjusted in accordance with the thickness of the soles being operated upon. A treadle (not shown) is connected to the lower end of the rod 16 so that the operator may conveniently separate the feed roll and work support in introducing the edge of the sole between the feed roll and work support, or in removing the work.

In order that the skiving knife may operate properly to remove a skiving from the outer edge of the sole, and may also operate to remove a skiving of substantially uniform thickness, the knife is mounted to move with the head 12, and is thus maintained in fixed relation to the feed roll regardless of variations in the thickness of the sole being operated upon.

In order that the skiving knife may operate properly to remove the desired skiving from the lower edge of the outsole, without danger of injury to the channel flap or to the outseam, a guard 22 is provided which is arranged to lie between the feed roll and the channel flap, and thus prevent the inadvertent guiding of the shoe in a manner to injure the channel flap, or to bring the outseam into position to be acted upon by the skiving knife. In order that the guard may be located to enable the skiving cutter to cut close up to the channel flap, or any desired distance from the channel flap, the guard is so mounted that it may be adjusted transversely of the line of feed. In the construction shown, the guard is formed on the outer end of an arm 23, the rear end of which is secured to the adjustable slide 23^a by a bolt 24 which passes through a slot formed in the slide. By thus mounting the guard it may be adjusted to vary its position with relation to the feed wheel 2 and with relation to the knife, so that the skiving knife may cut at any desired distance from the channel flap when the guard is in engagement with the flap. The adjustments also enable the guard to be so adjusted that it may be utilized as a gage for guiding the work by engagement with the channel flap, and may thus coöperate with the crease gage formed by the work support in guiding the work when skiving the sole through the shank, or may act as a gage for guiding the work by engagement with the channel flap in utilizing the machine to skive the lower edge of the sole around the forepart.

Since the guard 22 is secured to the head 12, which also carries the feed roll and skiving knife, the lower edge of the guard is maintained in fixed relation to the feed wheel and knife, and may be so arranged that it will act as a gage or presser foot for engaging the outsole channel to determine the depth to which the teeth of the feed wheel shall penetrate the work, and to also insure the removal of a uniform skiving.

from the edge of the sole by the skiving knife. In the embodiment of the invention shown, therefore, the guard 22 performs the function of a guard for preventing injury to the channel flap or outseam, and also performs the function of a gage or presser foot for engaging the channel and controlling the action of the feed roll and skiving knife upon the lower outer edge of the sole, and may also perform the function of a gage which either alone or in conjunction with the work support enables the operator to properly guide the work to remove the skiving at the desired distance from the channel flap in operating about the forepart or through the shank, as the case may be.

In order that the feed roll may be adjusted with relation to the work support, to act upon that part of the sole edge which is removed by the skiving knife, the shaft 10 is so mounted that it may be adjusted longitudinally. This adjustment is provided for by retaining the shaft in its bearings by collars 25 which engage the ends of the bearings, and which may be adjusted to vary the longitudinal position of the shaft.

In order that the skiving knife may be adjusted to bring its cutting edge into proper position to remove the desired skiving from the lower edge of the sole, the knife is so mounted upon the head 12 that it may be given a horizontal adjustment transversely of the direction of the feed, an adjustment in the direction of the feed, an angular adjustment, and a vertical adjustment. The horizontal adjustment transversely of the direction of the feed is provided for by clamping the shank of the knife between clamping jaws 26 of a supporting arm 27, the knife being held in adjusted position by a clamping screw 28. By this adjustment the skiving knife may be properly located with relation to the crease gage, or with relation to the gage for engaging the channel flap to cut close up to the channel flap or at any desired distance from the channel flap. The adjustment of the knife in the direction of the line of feed is provided for by mounting the arm 27 on a guideway formed on a support 29, and securing the arm in position upon the support by a clamping bolt 30 which passes through a slot in the arm. The angular adjustment of the skiving knife is provided for by mounting the support 29 upon a segmental guideway formed upon a slide 31, and securing the support in adjusted position by a clamping bolt 32. The segmental guideway is so formed that it is substantially concentric with the end of the skiving knife, and by adjusting the support 29 upon the segmental guideway, the angular adjustment of the knife may be varied to produce the desired bevel upon the lower outer edge of the sole. In order that the knife may be

adjusted vertically, the slide 31 is mounted upon a vertical guideway formed on a bracket 33 formed on the side of the head 12. An adjusting screw 34 is provided for adjusting the slide 31, and the slide is clamped in adjusted position by the clamping bolts 35.

In operating upon the shanks of shoes, the work support may be used as a crease gage for guiding the shoe by engagement with the inseam or last, and in such case the guard 22 may be adjusted so that it may be utilized by the operator as a gage for engaging the channel flap, and thus enabling him to readily determine when the shoe is being held in proper position to remove the skiving without danger of injury to the channel flap or to the outseam, or may be adjusted so that it does not engage the channel flap when the shoe is held in proper position. In the latter case the guard will act to prevent accidental displacement of the shoe sufficient to cause injury to the channel flap or outseam. In either case the stop 19 which determines the lower position of the feed roll and knife should be so adjusted that the lower edge of the guard will ride along the channel outside the channel flap, and act as a gage for controlling the depth to which the skiving knife will cut, and the depth to which the feed wheel may penetrate the work. In operating upon the foreparts of shoes provided with extension edge soles the projection of which from the inseam or last varies around the shoe, the guard 22 may be so adjusted or located that it may be used as a gage for guiding the shoe by engagement with the channel flap. Since the channel flap is located at a uniform distance from the edge of the sole, the use of a gage to guide the shoe by engagement with the channel flap enables a uniform skiving to be removed from the lower outer edge of the sole about the forepart without danger of injury to the channel flap or to the outseam.

While it is preferred to employ the construction and arrangement of devices shown and described, it will be understood that this construction and arrangement is not material to the invention except so far as it is specified in the claims, and may be varied and modified without departing from the broader features of the invention.

Having explained the nature and object of the invention, and specifically described one form of machine in which it may be embodied, what we claim is:

1. A skiving machine, having, in combination, a work support arranged to support the projecting edge of the sole of a shoe in position to be acted upon by a skiving knife and a feed roll relatively yielding to compensate for variations in the thickness of the sole, and a skiving knife blade maintained in fixed relation to the feed roll with

its edge continuously in position to shave a skiving from the lower outer margin of the sole, substantially as described.

2. A skiving machine, having, in combination, a work support arranged to support the projecting edge of the sole of a shoe in position to be acted upon by a skiving knife; a coöperating feed roll, a yielding head in which the feed roll is mounted, and a skiving knife blade carried by the head with its edge continuously in position to shave a skiving from the lower outer margin of the sole, substantially as described.

3. A skiving machine, having, in combination, a work support arranged to support the projecting edge of the sole of a shoe in position to be fed against the edge of a skiving knife, a feed roll arranged to engage the lower surface of the sole outside the channel flap, a skiving knife extending between the feed roll and work support, and a gage for guiding the shoe by the channel flap, substantially as described.

4. A skiving machine, having, in combination, a skiving knife for removing a skiving from the lower outer margin of the outsole, a work support arranged to support the projecting edge of the sole of a shoe in position to be acted upon by the knife, a feed roll, a guard arranged between the feed roll and channel flap, and means for relatively adjusting the guard and the feed roll and knife, substantially as described.

5. A skiving machine, having, in combination, a work support and feed roll arranged to engage respectively the upper and lower sides of the projecting edge of the sole of a shoe and supported for relative movement to compensate for variations in the thickness of the sole passing between them, a skiving knife blade maintained in fixed relation to the feed roll with its edge in position to shave a skiving from the lower outer margin of the sole, and a gage maintained in fixed relation to the skiving knife and feed roll and arranged to engage the lower side of the outsole, substantially as described.

6. A skiving machine, having, in combination, a work support arranged to support the projecting edge of the sole of a shoe in position to be acted upon by a skiving knife, a coöperating feed roll, a skiving knife blade having its edge in position to shave a skiving from the lower outer margin of the sole, and a guard and depth gage arranged to engage the outsole channel, substantially as described.

7. A skiving machine, having, in combination, a work support arranged to form a crease gage and to support the projecting edge of the sole of a shoe in position to be fed against the edge of a skiving knife and a feed roll relatively yielding to compensate for variations in the thickness of the

sole arranged to engage the lower outer edge of the sole outside the channel flap, and a skiving knife extending between the feed roll and work support and maintained in fixed relation to the feed roll, substantially as described.

8. A skiving machine, having, in combination, a work support arranged to form a crease gage and to support the projecting edge of the sole of a shoe in position to be acted upon by a skiving knife, a relatively yielding feed roll arranged to engage the lower outer edge of the sole, a skiving knife blade having its edge in position to shave a skiving from the lower outer margin of the sole and maintained in fixed relation to the feed roll, and a guard arranged to lie in the channel, substantially as described.

9. A skiving machine, having, in combination, devices adapted to engage the opposite surfaces of a channeled, attached outsole, for feeding the same, a channel guard, and a skiver extending between the devices and terminating adjacent the guard, substantially as described.

10. A skiving machine, having, in combination, devices adapted to engage the opposite surfaces of a channeled, attached outsole, for feeding the same, a channel guard, a skiver extending inwardly between the devices and terminating adjacent the guard, and means for independently adjusting the guard to position the feeding devices and skiver relative to the work, substantially as described.

11. A skiving machine, having, in combination, a channel guard blade, and a skiving blade extended into angular juxtaposition, and a feeding roller operating within the angle upon one surface of the sole, substantially as described.

12. A skiving machine, having, in combination, feeding devices adapted to engage the opposite surfaces of a channeled attached outsole, one set of devices being rotary for feeding the sole, a rigid guard blade arranged upon the channel side of the feed devices, and a skiver extending between the feed devices and terminating adjacent the guard, substantially as described.

13. A skiving machine, having, in combination, devices adapted to engage the opposite surfaces of a channeled attached outsole for feeding the same, a channel guard, a skiver extending inwardly between the devices and terminating adjacent the guard, and means for adjusting the guard transversely to the direction of the feed to position the feeding devices and skiver relatively to the work, substantially as described.

14. A skiving machine, having, in combination, devices adapted to engage the opposite surfaces of a channeled attached outsole for feeding the same, a channel guard, a skiver extending inwardly between the de-

- vices and terminating adjacent the guard, and means for adjusting the guard vertically to determine the depth of cut, substantially as described.
5. 15. A skiving machine, having, in combination, a skiving knife for removing a skiving from the lower outer margin of the sole of a shoe, a work support arranged to support the projecting edge of the sole of a shoe in position to be acted upon by the knife, a feed roll arranged to engage the lower surface of the sole outside the channel flap, and a guard arranged between the channel flap and the feed roll and knife for preventing injury to the channel flap or outseam, substantially as described.
10. 16. A skiving machine, having, in combination, a skiving knife having its edge arranged to shave a skiving from the lower outer margin of the outsole of a shoe, a work support arranged to support the projecting edge of the sole of a shoe in position to be fed against the edge of the knife, a feed roll arranged to engage the lower surface of the sole outside the channel flap, and a gage for guiding the shoe by engagement with the channel flap, substantially as described.
15. 17. A skiving machine, having, in combination, a work support and feed roll, arranged to engage respectively the upper and lower sides of the projecting edge of the sole of a shoe and supported for relative movement to compensate for variations in the thickness of the sole passing between them, a skiving knife blade having its edge in position to shave a skiving from the lower outer margin of the sole, and a gage maintained in fixed relation to the skiving knife and arranged to engage the lower side of the outsole, substantially as described.
20. 18. A skiving machine, having, in combination, a work support and feed device arranged to engage respectively the upper and lower sides of the projecting edge of the sole of a shoe, and supported for relative movement to compensate for variations in the thickness of the sole passing between them, a gage arranged to engage the lower side of the outsole, and a skiving knife blade having its edge in position to shave a skiving from the lower outer margin of the sole and maintained in fixed relation to the gage, substantially as described.
25. 19. A skiving machine, having, in combination, a work support arranged to support the projecting edge of the sole of a shoe in position to be acted upon by a skiving knife, a coöoperating feed device, a skiving knife having its edge in position to shave a skiving from the lower outer margin of the sole, and a guard and depth gage maintained in fixed relation to the knife and arranged to engage the outsole channel, substantially as described.
30. 20. A skiving machine, having, in combination, devices adapted to engage the opposite surfaces of a channeled, attached outsole, for feeding the same, a skiver extending inwardly between the devices with its edge in position to shave a skiving from the outer margin of the sole, a gage engaging the sole outside the channel flap, and means for adjusting the gage, substantially as described.
35. In testimony whereof we affix our signatures, in presence of two witnesses.
